CLAIM

The ornamental design for a gutter guard assembly, as shown and described.

DESCRIPTION

FIG. 1 is a perspective view of a gutter guard assembly; FIG. 2 is a top plan view of the gutter guard assembly of FIG. 1;

FIG. 3 is a bottom plan view of the gutter guard assembly of FIG. 1;

FIG. 4 is a left-side elevation view of the gutter guard assembly of FIG. 1;

FIG. 5 is a right-side elevation view of the gutter guard assembly of FIG. 1;

FIG. 6 is a front elevation view of the gutter guard assembly of FIG. 1; and,

FIG. 7 is a rear elevation view of the gutter guard assembly of FIG. 1.

The broken lines shown in the drawings depict portions of the gutter guard assembly that form no part of the claim.
